HOME HUMIDIFYING SYSTEM

Arthur B. Favor, Llanerch, Pa.

Application August 27, 1941, Serial No. 408,446

2 Claims. (Cl. 237—1)

The principal object of the present invention is to provide a comparatively simple, reliable and inexpensive apparatus, devoid of electrical connections, and which shall be silent, efficient and self-controlled in operation and shall operate in conjunction with a house heating plant to automatically humidify the atmosphere or air of the house in consonance with the temperature thereof.

Other objects of the invention will appear from the following description at the end of which the invention will be claimed.

Generally stated, the invention comprises in connection with a heater having a fire box which generates heat for heating a house; the use of a boiler arranged in the fire box and heated in consonance with the heat generated for house space heating; a tank and float valve coordinated with the feed pipe supplying what may be described as a trickle of water at low pressure to the boiler and causing it to operate as a flash boiler in a noiseless manner; a pipe leading from the boiler and discharging steam into the house space; regulating valves and a condenser tank connected with the last mentioned pipe for adjusting the steam output from the boiler to the moisture requirements of the house, and drain connections.

The invention also comprises the improvements to be presently described and finally claimed.

In the following description reference will be made to the accompanying drawing forming part hereof and in which the single figure is a diagrammatic view partly in section and partly in elevation illustrating features of the invention.

Referring to the drawing, 1 indicates a small boiler which is operated as a flash boiler as will be hereinafter explained. This boiler is inserted in any convenient way in the fire box of the house heater not shown because too well understood to require description or illustration. The boiler 1 is automatically fed with water from a tank 2 in which the float valve 3 maintains a substantially constant level indicated at b—b. The output of steam from the boiler 1 is introduced to the interior of the house, for example by means of a nozzle 4 placed under a large suitably located radiator a. The steam introduced through the nozzle 4 is controlled by two valves 5 and 6 which adjust the steam output to the moisture requirements of the house and which when once set need not be changed throughout the heating season, because the moisture output is proportional to the operation and drying effect

of the heating system. The water supply is maintained by a tap on the cold water supply line 7 with a small tubing 8 to the float valve 3 located in the tank 2 which may be of two gallon capacity. The tank 2 is so located that it maintains through a small tubing line 9 a small supply of water in the flash boiler 1 when cool, for example about one and one-half inches in the boiler. The boiler 1 is located in the fire box of the house heating furnace preferably on the inside of a door in place of insulation or at some other convenient place which will least interfere with the operation of the heater or main boiler. When heat is generated in the fire box the water in the boiler 1 is soon evaporated and since the boiler 1 is fed by a small line 9 at very low pressure the ensuing trickle or modicum of water causes the boiler to act as a flash boiler in a noiseless manner. The steam thus generated passes out and up an insulated copper tube 10 to the nozzle 4. Provision is made in the line 10 for safety, condensation and regulation. A T-fitting is installed close to the boiler to drain off condensate and provide fool proof safety by running a tube 11 from it to the bottom of the water supply tank 2, thus providing a seal and at the same time preventing the accumulation of any appreciable pressure. Further up the line 10 another T is installed with the valve 6 close to its outlet. From the valve 6 a tube 12 is run to the small fin radiator or some other form of condenser 13, the outlet of which is piped as at 14 back to the water tank 2. The valve and condenser provide means for taking care of surplus steam and form one of the control mediums. Immediately after passing through this T another valve 5 is installed which provides the other medium of control and regulates the amount of steam passing out of the nozzle 4 and up into the house space. 15 is a drip pan arranged under the radiator a, and having a depending tube 16 through which the nozzle 4 passes and this tube 16 is connected through a trap 16a by a pipe 17 to discharge into the tank 2. The purpose of the drip pan is to catch any condensate which might drip from the radiator when the boiler 1 first starts up with the radiator cold. There is a valve 18 provided in the pipe 8. 19 is a drain valve at the bottom of the water tank 2. 20 is a valve in the line 9 and it is useful to facilitate removing the boiler 1 if necessary and also for cutting down or adjusting the water supply to the boiler to insure that it shall operate as a flash boiler. 21 is a tap and drain valve useful in cleaning the boiler 1.

Sediment is largely excluded from the boiler and supply line by extending its open end in the water tank upward.

With the described apparatus there is no difficulty in maintaining 50% humidity in a house. The controls 5 and 6 need never be touched except in spring and fall when outside moisture is high and the heater only runs occasionally. At such times steam is shut off from the house. Steam does not appear in a visible cloud around the radiator a, nor does it loosen adjacent wall paper as might be supposed. There is no trouble from the radiator rusting in spite of tests showing that the system may introduce as much as ten gallons of water to the house atmosphere in one day. The benefits from such a system are many and are varied; such as comfort at 70°, less washing of window curtains due to keeping down fine dust; furniture remains tight by not drying out unduly; house plants thrive, and above all common colds and nose and throat ailments are reduced.

It will be obvious to those skilled in the art to which the invention relates that modifications may be made in details of construction and arrangement without departing from the spirit of the invention which is not limited in respect to such matters or to matters of mere form.

I claim:

1. A house space humidifier for use with a house space heating system including a heater with a fire box which generates heat for heating the house space, comprising a boiler arranged in the fire box and heated in consonance with the heat generated for house space heating, a

tank and a float valve and coordinated feed pipe of relatively restricted capacity and directly connected to the boiler and supplying a modicum of water to the boiler and causing it to operate as a flash boiler in a noiseless manner, a steam outlet pipe leading directly from the boiler to and discharging into the house space, a condenser tank, a bleeder pipe from the steam pipe to the condenser, regulating valves connected with the last mentioned pipes for adjusting the steam output from the boiler to the moisture requirements of the house and for directing steam in excess of those requirements to the condenser tank, and drain connections for the condenser tank.

2. A house space humidifier for use with a house space heating system including a heater having a fire box which generates heat for heating radiators, a boiler adjacent the fire box and heated in consonance with the heat generated for house space heating, a tank and float valve water connections coordinated with a feed pipe supplying a trickle of water to the boiler and causing it to operate as a flash boiler, a drip pan and nozzle arranged under a radiator, a pipe leading from the boiler and discharging through the nozzle, regulating valves and a condenser tank connected with the last mentioned pipe for adjusting the steam output from the nozzle to the moisture requirements of the house, pipe connections from the drip pan including a trap to the tank, and a pipe connection from near the bottom of the tank to the steam line that leads from the boiler.

ARTHUR B. FAVOR.
